SYNCHRONIZING SIGNAL GENERATOR

Clyde E. Hallmark, Fort Wayne, Ind., assignor to
 Farnsworth Television and Radio Corporation,
 a corporation of Delaware

Application November 18, 1943, Serial No. 510,759

4 Claims. (Cl. 178—7.2)

1

This invention relates to frequency generators and particularly to scanning frequency generators for television systems.

In television systems it is common practice to generate the scanning frequency voltages in such a manner that the frequencies of these voltages are maintained in a predetermined relationship with a standardizing frequency. It generally is convenient to utilize as the standardizing frequency a 60 cycle alternating current derived from a commercial power source. According to the present RMA standards video signals are transmitted at the rate of 30 frames per second. Each frame comprises an odd number of scanning lines and, where a 2 to 1 interlaced scanning pattern is used, the field scanning frequency is 60 cycles per second.

The scanning frequencies usually are derived from an oscillator which is operated either at a high or a low frequency. In the case of a low frequency oscillator its frequency ordinarily is 60 cycles per second and its output voltage is multiplied in frequency to twice the line scanning frequency. Such an expedient is necessary for the reason that the line scanning frequency for an odd number of scanning lines is not an even harmonic of the 60 cycle oscillator frequency when a 2 to 1 interlaced scanning pattern is used. The line scanning frequency is derived from the voltage having twice the line scanning frequency by the use of a frequency divider. The 60 cycle frequency for the oscillator generally is chosen for the reason that it conforms to the field scanning frequency and also to the frequency of the standardizing source. Numerous arrangements have been utilized for comparing the 60 cycle oscillator frequency with the 60 cycle alternating current derived from a commercial power source and for utilizing the output of the frequency comparator to control the oscillator frequency so that it will be in agreement at all times with the source of a standardizing frequency.

In an arrangement where the oscillator is operated at a high frequency it also is necessary, in order to derive the low frequency scanning voltages and a voltage suitable for comparison with the standardizing source, to employ a number of frequency dividers.

It is an object of the instant invention, therefore, to provide a novel means for generating television scanning voltages definitely related in frequency to a standardizing frequency and in which the use of frequency dividing apparatus is obviated.

2

Where it is desired to control the frequency of an oscillator automatically, it is customary to use a so-called LC type of oscillator for the reason that a reactance tube may be employed as the frequency varying means. However, it frequently is desirable to use a so-called RC type of oscillator but, a device of this character is not susceptible of automatic frequency control by means of a conventional reactance tube.

10 Another object of the invention is to provide a novel automatic frequency control for an RC type of oscillation generator.

In accordance with the present invention there is provided a means for producing oscillations of a distorted wave form at a submultiple frequency of the standardizing source. The distorted wave form contains a number of harmonics of the submultiple frequency, one of which is nominally equal to the frequency of the standardizing source. This harmonic and the standardizing frequency are compared to develop an automatic frequency control voltage for employment in connection with the oscillator.

The form of oscillation generator utilized comprises a vacuum tube having the output and input circuits thereof coupled by a phase shifting network for the feedback of output circuit energy to the input circuit. The network comprises a plurality of meshes, each including resistance and reactance of one type only. The resistance element of one of the phase shifting meshes consists of the space discharge path of a vacuum tube. The magnitude of this resistance element is varied by the automatic frequency control voltage to vary the total phase shift of the feedback energy and, thus, vary the frequency of oscillation.

For a better understanding of the invention, together with other and further objects thereof, reference is had to the following description taken in connection with the accompanying drawing, and its scope will be pointed out in the appended claims.

In the drawing, the single figure is a schematic circuit diagram of a scanning frequency generator and automatic frequency control apparatus embodying the invention.

Having reference now to the drawing, it is assumed that it is desired to generate scanning voltages for a television system employing an odd number of scanning lines per frame and 30 frames per second with a 2 to 1 interlaced scanning pattern. In such a case the frequency of the field scanning voltage will be 60 cycles per second. Also, in this case the source of stand-

ardizing frequency is assumed to be a conventional 60 cycle source of commercial alternating current. In accordance with the invention then, the oscillation generator is arranged to develop sinusoidal voltage at a sub-harmonic frequency of the frame scanning frequency of 60 cycles. For illustrative purposes the first sub-harmonic of 30 cycles per second will be utilized.

The oscillation generator comprises a vacuum tube 1 which, in the present instance, is illustrated as a pentode. However, it is contemplated that other types of tubes may be employed with equal facility without departing from the spirit or scope of the invention. The cathode of the tube 1 is connected to ground and the anode is connected through a load inductor 2 to the positive terminal of a source of direct current such as a battery 3, of which the negative terminal is connected to ground. The suppressor grid 4 of the tube 1 is connected directly to ground and the screen grid 5 is connected through a resistor 6 to the positive terminal of the battery 3 and also through a by-pass condenser 7 to ground.

The anode of the tube 1 is connected to a triple mesh phase shifting network of capacitance and resistance elements. As illustrated, the network is formed of series condensers and shunt resistors. It is contemplated that a network of series resistors and shunt condensers are within the scope of this invention. Condensers 8, 9 and 11 comprise, respectively, the capacitance elements of the first, second and third network meshes. The resistance elements of the successive network meshes comprise, respectively, the space discharge path of a triode vacuum tube 12, and resistors 13 and 14. The network is terminated in a resistor 15, one terminal of which is grounded and the other terminal is connected through a resistor 16 to the control grid 17 of the oscillator tube 1. The control grid also is by-passed to ground by a condenser 18.

The anode of the oscillator tube 1 is coupled by a condenser 19 to the control grid 21 of a pentode vacuum tube 22 serving as the wave form distorts. A resistor 23, connected between the control grid of the tube 22 and ground, serves as the grid leak resistance for this coupling circuit. The screen grid 24 of the tube 22 is connected through a resistor 25 to the positive terminal of the battery 3 and the suppressor grid 26 is connected directly to ground. The anode of the tube 22 is connected through an inductor 27, which is by-passed by a condenser 28, and through the resistor 25 to the positive terminal of the battery 3. The cathode of the tube is connected through a self-biasing resistor 29 to ground and a condenser 31 is connected to bypass the resistor 29. The self-bias voltage developed by this arrangement is to cause the tube to operate in the anode current saturation region.

The apparatus for selecting the low frequency scanning voltage of 60 cycles per second and the voltage for comparison with the source of standardizing frequency includes a pentode vacuum tube 32. The cathode and the suppressor grid 33 of this tube are connected directly to ground. The anode of the tube 32 is connected through a load resistor 34 to the positive terminal of the battery 3. The screen grid 35 is connected through a resistor 36 to the positive terminal of the battery 3 and also is by-passed to ground by a condenser 37. As in the case of the oscillator tube 1, the low frequency selector tube 32 is provided with a phase shifting network similar to that connected to the oscillator tube. The se-

lector tube network includes series condensers 38, 39 and 41, the latter of which preferably is adjustable so as to provide for an adjustment in the natural oscillation period of the selector circuit. The shunt elements of the phase shifting network are resistors 42, 43 and 44, the latter of which preferably is in the form of a potentiometer, having an adjustable contact 45. The contact 45 is connected through a resistor 46 to the control grid 47 of the selector tube 32. The control grid of this tube also is by-passed to ground by a condenser 48. Although the phase shifting networks associated with tubes 1 and 32 are similar, the output energy feedback to the input circuit, in the case of tube 1, is sufficient to sustain oscillation at a frequency of 30 cycles per second, whereas, in the case of tube 32, the feedback energy is insufficient to sustain oscillation. It is merely sufficient to enable the tube 32 to act as a frequency selective amplifier responsive only to a frequency of 60 cycles per second.

In order to furnish a control voltage for driving the selector tube 32 at the desired frequency of 60 cycles per second, the anode of the distortion tube 22 is coupled by an arrangement including a condenser 49 and a resistor 51 to the control grid 47 of the selector tube. Preferably, the resistor 51 is in the form of a potentiometer having an adjustable contact 52 which is connected by a resistor 53 to the potentiometer contact 45 in the feedback circuit of the selector tube 32 and also through a resistor 46 to the grid 47 of the tube.

The anode of the selector tube 32 is coupled by means of a condenser 54 and a potentiometer 55, having an adjustable contact 56, to the phase comparator. This apparatus includes a diode 57 having an anode which is connected to ground through a resistor 58 and also to the potentiometer contact 55 through a condenser 59. The cathode of the diode 57 is connected to an adjustable contact 61 of a potentiometer 62, of which the terminals are connected to a grounded source of a standard 60 cycle alternating current source connected to the terminals 63.

The automatic frequency control voltage developed by the phase comparator is impressed upon the frequency determining circuit of the oscillator tube 1 by means of a connection from the anode of the diode 57 through a resistor 64 to the control grid of the triode 12. The control grid of this tube is connected to an adjustable contact 65 of a potentiometer 66 and also through a filter condenser 67 to ground. The terminals of the potentiometer are connected to the terminals of a source of biasing voltage such as a battery 68.

The anode of the distortion tube 22 also is coupled to a high frequency selecting circuit 69 by means of a condenser 70. The selector 69 may be substantially similar to the selector including the pentode tube 32, except that the phase shifting network therefor is designed to operate the high frequency selector at the line scanning frequency.

The output circuit of the field scanning frequency selector including the tube 32, is connected to a vertical scanning generator 71. Similarly, the output circuit of the line scanning frequency selector 69 is connected to a horizontal scanning generator 72. The scanning generators 71 and 72 may be conventional and are not shown in detail herein for the reason that they form no part of the present invention.

Referring now to the operation of the illustra-

tive embodiment of the invention, assume that the oscillator tube 1, together with its frequency determining circuit including the series condensers 8, 9 and 11 and the shunt triode 12 and resistors 13, 14 and 15, effects the generation of a voltage of sinusoidal wave form having a frequency of 30 cycles per second. This frequency is determined by the parameters of the phase shifting meshes connected between the output and input circuits of the tube. Each mesh, including a series condenser, such as 9, and a shunt resistor, such as 13, effects a phase shift, in the instant embodiment of the invention, of approximately 60° in the voltage of that portion of the energy delivered by the output circuit of the tube to the frequency determining circuit. Thus, with the three disclosed meshes of this character, the voltage of this energy is shifted 180° in phase. This phase-shifted energy is impressed upon the input circuit of the tube 1 in sufficient magnitude to produce sustained oscillations in the output circuit. The oscillator frequency may be varied by adjusting one or more of the frequency determining circuit parameters, for example, the value of one of the shunt resistors. A modification of the shunt resistance consisting of the triode 12 will effect a change in the amount of phase shift produced by the first mesh. Consequently, a similar change will be effected in the total phase shift, thereby to change the oscillation frequency.

The sine wave voltage derived from the oscillator tube 1 is converted by the distortion tube 22 into a substantially rectangular wave form voltage having a frequency of 30 cycles per second. The rectangular wave form voltage is produced by driving the tube to saturation through the use of the self-biasing resistor 29. A rectangular wave form is referred to merely for illustrative purposes. Substantially any distorted wave form containing the desired harmonics will serve with equal facility.

A portion of the energy of the rectangular wave form voltage is employed to drive the low frequency selector, including the tube 32, in a manner to develop in the output circuit of this tube a substantially sinusoidal voltage having a frequency of 60 cycles per second which is the second harmonic of the generated frequency. The natural period of the network including the series condensers 38, 39 and 41 and the shunt resistors 42, 43 and 44 is substantially 60 cycles per second. By means of the adjustment of the potentiometer contact 45 the magnitude of the phase-shifted energy developed in the network is maintained below the value necessary to sustain oscillations in the output circuit of the tube 32. This energy is combined with enough 60 cycle energy derived from the rectangular wave form voltage, as determined by the adjustment of the potentiometer contact 52, to produce feedback energy at 60 cycles per second of sufficient magnitude to drive the tube 32 at this frequency.

The phase comparator, including the diode 51, functions to detect deviations of the 60 cycle derived frequency from the standard 60 cycle frequency. These frequency deviations are manifested as phase displacements of the derived voltage wave with respect to the standardizing voltage wave. The voltage of the diode cathode varies sinusoidally under the control of the standardizing frequency voltage derived from the potentiometer 62. The voltage of the diode anode also varies sinusoidally under the control of the oscillator derived voltage impressed upon it by

the condenser 59. So long as the cathode and anode voltages are in phase the anode-to-cathode potential of the diode remains constant and the current conduction through the diode and the resistor 58 is maintained at a constant value which is dependent upon the relative magnitudes of the anode and cathode voltages. A phase deviation of these voltages effects a corresponding change in the diode anode-to-cathode potential and, consequently, in the value of the current conduction through the diode and the resistor 58. Thus, a unidirectional voltage is developed in the resistor of a magnitude corresponding to the degree of the phase deviation.

This unidirectional voltage is combined with the biasing voltage derived from the potentiometer 66 to form an automatic frequency control voltage. The magnitude and polarity of this control voltage represents the instantaneous phase deviations of the oscillator derived 60 cycle voltage from the voltage derived from the standardizing source. The control voltage is impressed upon the grid of the triode 12 in the manner described. Any alternating current component which may be present in the voltage derived from the output circuit of the diode 51 is substantially eliminated from the frequency control voltage by the filter condenser 67. The control voltage impressed upon the grid of the triode 12 effectively varies the impedance of the space discharge path of this tube. A variation in this impedance effects a corresponding variation in the degree of phase shift produced in the first mesh of the phase shifting network connected between the output and input circuits of the oscillator tube 1. Thus, the phase of the feedback energy impressed upon the input circuit of the oscillator tube is altered in one sense or the other, thereby to effect a corresponding change in the frequency of the generated voltage.

The frequency of the voltage developed in the output circuit of the low frequency selector tube 32, being 60 cycles per second, is suitable for controlling the generation of the field scanning voltage since it is desired that this voltage be generated at this frequency. The harmonic of the generated 30 cycle voltage, which the high frequency selector 69 derives from the rectangular 30 cycle wave developed in the output circuit of the distortion tube 22, produces a voltage in the output circuit of the high frequency selector having the desired line scanning frequency.

While it will be understood that the circuit specifications of a scanning frequency generator embodying this invention may vary according to the frequency requirements of any particular television system, the following circuit specifications for a generator employed to develop voltages at 60 cycles per second and 15,750 cycles per second are included, by way of example only:

Vacuum tubes 1 and 32	6AC7
Inductor 2	henries 100
Battery 3	volts 250
Resistors 6 and 36	ohms 82,000
Condenser 7	microfarads 35
Condensers 8, 9 and 28	do 0.17
Condenser 11	do 0.20
Vacuum tube 12	6C8G
Resistors 13, 14, 15, 34, 42, 43, 44 and 53	ohms 10,000
Resistors 16 and 46	do 330
Condensers 18 and 48	micro-micro-farads 200
Condenser 19	microfarads 4
Vacuum tube 22	6SJ7

Resistors 23, 58 and 66	megohm	1
Resistor 25	ohms	50,000
Inductor 27	henries	17
Resistor 29	ohms	25,000
Condenser 31	microfarads	0.5
Condenser 37	do	40
Condensers 38 and 39	do	0.05
Condenser 41	do	0.132
Condensers 49 and 70	do	0.5
Resistors 51 and 55	ohms	100,000
Condenser 54	microfarads	1
Vacuum tube 57		6H6
Condenser 59	microfarads	0.1
Resistor 62	ohms	1,000
Resistor 64	do	230,000
Condenser 67	microfarads	0.1
Battery 68	volts	12

It is evident that a scanning frequency generator in accordance with the instant invention possesses a number of advantageous features not previously realizable in prior art systems. Since the line scanning frequency and the field scanning frequency are not related harmonically in a system, where an odd number of scanning lines per frame and an even number of interlaced fields per frame are necessary, the generation of a sub-harmonic of the field scanning frequency makes it possible to dispense with the multiplicity of frequency dividers and/or frequency multipliers required in prior art systems. Also, when using an oscillator of the type described, the application of an automatic frequency control voltage thereto in the novel manner disclosed makes it possible to positively lock the frequency of the oscillator in a predetermined relationship to a source of standardizing frequency.

While there has been described what, at present, is considered the preferred embodiment of the invention, it will be obvious to those skilled in the art that various changes and modifications may be made therein without departing from the invention, and therefore, it is aimed in the appended claims to cover all such changes and modifications as fall within the true spirit and scope of the invention.

What is claimed is:

1. In a scanning frequency generator for a television system, means for producing oscillations of a distorted wave form at a submultiple frequency of a low frequency field scanning voltage and containing a plurality of harmonics of said submultiple frequency, means coupled to said oscillation producing means and controlled by a harmonic of said distorted wave form oscillations to produce a deflecting voltage for said television system at field scanning frequency, and means coupled to said oscillation producing means and controlled by another harmonic of said distorted wave form oscillations to produce a deflecting voltage for said television system at line scanning frequency.

2. In a scanning frequency generator for a television system, means for producing oscillations

tions of a distorted wave form at a submultiple frequency of a low frequency field scanning voltage and containing a plurality of harmonics of said submultiple frequency, means including a low frequency selector coupled to said oscillation producing means to produce a deflecting voltage for said television system at field scanning frequency, and means including a high frequency selector coupled to said oscillation producing means to produce a deflecting voltage for said television system at line scanning frequency.

3. In a scanning frequency generator for a television system, an electronic oscillation generator for producing sinusoidal oscillations at a submultiple frequency of a low frequency scanning voltage, means for converting said sinusoidal oscillations into oscillations of a substantially rectangular wave form, said rectangular oscillations being produced at said submultiple frequency and containing substantially all harmonics of said submultiple frequency, a low frequency selector coupled to said wave form converting means to produce a control voltage at the low scanning frequency, a generator coupled to said low frequency selector for control thereby to produce a deflecting voltage for said television system at field scanning frequency, a high frequency selector coupled to said wave form converting means to produce a control voltage at the high scanning frequency, and another voltage generator coupled to said high frequency selector for control thereby to produce a deflecting voltage for said television system at line scanning frequency.

4. In a scanning frequency generator for a television system, an electronic oscillation generator for producing sinusoidal oscillations at a submultiple frequency of a low frequency scanning voltage, a distorting vacuum tube for converting said sinusoidal oscillations into oscillations of a substantially rectangular wave form, said rectangular oscillations being produced at said submultiple frequency and containing substantially all harmonics of said submultiple frequency, a low frequency selector including a driven oscillator coupled to the output circuit of said distorting tube to produce a control voltage at the low scanning frequency, the natural period of oscillation of said low frequency selector oscillator being equal to the low frequency scanning voltage, a vertical scanning voltage generator coupled to said low frequency selector for control by said low frequency control voltage to produce a deflecting voltage for said television system at field scanning frequency, a high frequency selector coupled to the output circuit of said distorting tube to produce a control voltage at the high scanning frequency, and a horizontal scanning voltage generator coupled to said high frequency selector for control by said high frequency control voltage to produce a deflecting voltage for said television system at line scanning frequency.

CLYDE E. HALLMARK.
